his attorney

UNITED STATES PATENT OFFICE.

JAMES J. PHILLIPS, OF ROCHESTER, NEW YORK.

MOUNTING FOR TONE-ARMS OF TALKING-MACHINES.

1,288,168.

Specification of Letters Patent. Patented Dec. 17, 1918.

Application filed February 27, 1917. Serial No. 151,365.

To all whom it may concern:

Be it known that I, JAMES J. PHILLIPS, a citizen of the United States, and resident of Rochester, in the county of Monroe and State of New York, have invented certain new and useful Improvements in Mountings for Tone-Arms of Talking-Machines, of which the following is a specification.

The present invention relates to mountings for tone arms of talking machines, and an object thereof is to provide a simple and inexpensive construction which will permit the tone arm to swing across the record and, at the same time, have a movement toward and from the record.

To this and other ends, the invention consists of parts and combinations of parts all of which will be hereinafter described, the novel features being pointed out in the appended claims.

In the drawings:

Figure 1 is a sectional view through a tone arm showing the connection of the latter with the reproducer at one end and with the horn or amplifier of the talking machine at the other end, the reproducer being adjusted for operating upon talking machines of the hill and valley type;

Fig. 2 is a detail view showing the reproducer adjusted for operating upon records of the lateral wave type; and

Fig. 3 is a sectional view on the line *a—a*, Fig. 1.

Referring more particularly to the drawings, 1 indicates the casing of the talking machine which is provided, as usual, with the rotary record support 2 for the record 3. A sleeve 4 is supported by a flange 5 on the top of the casing 1, and connects with the horn or amplifier of the machine, such horn or amplifier being usually arranged in the casing below the top of the latter.

Connecting with the sleeve 4 is an elbow tube 8 which has its two arms lying at right angles, one arm fitting within the sleeve 4 so as to turn in said sleeve, and a piece of felt 9 or other non-conductor of sound being interposed between the sleeve and the elbow, for the purpose of preventing any vibrations in either one of said parts being transmitted to the other. To support the elbow 8 for turning in the sleeve 4 a pivot screw 10 may be employed, which turns loosely in the overhanging portion 7 of the bracket which projects upwardly from the sleeve 4. This pivot screw has a screw-threaded portion

which engages within an opening of a boss 11 formed on the elbow 8, the upper end of this boss coöperating with the under side of the overhanging portion 7 of the bracket 60 6, while the head 12 of the pivot screw co- 65 operates with the upper surface of the overhanging portion. To the end of preventing the screw from working loose during the swinging of the elbow, the screw is split at 13, and after the screw has been properly 70 adjusted its split end is spread apart, as shown in Fig. 1, to frictionally hold it against turning. At the same time, the screw may be removed by an ordinary screw 75 driver.

The tone arm is connected to the horizontally-presented arm of the elbow 8 by a joint which permits the tone arm to swing in a vertical plane on said elbow, while preventing the tone arm from swinging in a horizontal plane on the elbow. In this embodiment the joint comprises a ring 15 fitted to the tone arm and having a curved cross section so that a spherical or ball end is provided on the tone arm, this ball end fitting within the horizontally-presented arm of the elbow 8, and being mounted to swing in said elbow about the axis formed by two pins 16 arranged in alinement and extending 80 through the ring 15 and the walls of the elbow 8. The inner ends of these pins coöperate with the tone arm, while the outer ends of the pins are engaged by a ring 17 which is fitted tightly on the elbow 8 to cover said 85 pins. In this way both the pins are hidden and at the same time cannot become displaced.

The outer end of the tone arm may be bent slightly downwardly at 18 and in this downwardly-bent portion an elbow 19 may have one arm mounted to turn. In the other end of the elbow 19 the flange 20 of the reproducer 21 may be mounted to turn. By this arrangement the reproducer may be positioned, as shown in Fig. 1, for operation upon hill and valley records, or may be positioned, as shown in Fig. 2, for operation upon lateral wave records.

In the operation of the talking machine, 105 the tone arm 14 swings across the record 3 about the pivot screw 10 as an axis. The elbow 8 partakes of this swinging movement and connects with the sleeve 4 that leads to the horn, the connection being such that no 110 metallic contact exists between the elbow 8 and the walls of the sleeve 4 to conduct

metallic vibrations. While the elbow 8 partakes of the swinging movement of the tone arm, yet the latter may move independently of the elbow, so as to permit the rising and falling of the reproducer 21 on hill and valley records or the movement of the reproducer toward and from the record for the purpose of positioning the reproducer.

What I claim as my invention and desire 10 to secure by Letters Patent is:—

1. In combination with a stationary sleeve, an elbow having one arm turning in said sleeve, a tone arm connected to the elbow, a sound deadening ring interposed between 15 the outer wall of the elbow and the inner wall of the sleeve, an external supporting member, and means for suspending the elbow from the supporting member comprising a bearing pin secured against turning 20 on one of said parts and mounted to turn in the other of said parts, said bearing pin having at its free end a shoulder which engages the part in which the pin turns to sustain entirely the weight of the elbow.
2. In combination with a stationary sleeve, 25 a right-angled elbow having one arm mounted to turn in said sleeve about an axis coincident with the axis of said sleeve, a tone

arm having connection with the other arm of the elbow, and means for supporting said 30 elbow comprising an external bracket extending upwardly from the sleeve and having an overhanging portion provided with the opening coincident with the axis of turning of the sleeve, a boss on the sleeve coöperating 35 with the under side of said overhanging portion, and a headed pivot screw passing through the opening in the overhanging portion with its head coöperating with the upper side of said overhanging portion, and a screw-threaded portion extending into the boss, the under side being split so that the latter may be spread to prevent the free turning thereof.

3. In combination with an elbow, a tone 40 arm, a ring secured to the tone arm and having a curved cross section, said ring fitting in the elbow, two alined cylindrical pins passing through the elbow and the ring and having their inner ends abutting the 45 tone arm, and a ring surrounding said elbow and covering the outer ends of the pins.

JAMES J. PHILLIPS.
